UNITED STATES PATENT OFFICE.

THEODORE F. W. SCHMIDT, OF ANDERSON, INDIANA, ASSIGNOR OF ONE-HALF TO THE J. W. SEFTON MANUFACTURING COMPANY, OF SAME PLACE AND CHICAGO, ILLINOIS.

EGG-CASE.

SPECIFICATION forming part of Letters Patent No. 601,449, dated March 29, 1898.

Application filed September 27, 1897. Serial No. 653,187. (No model.)

To all whom it may concern:

Be it known that I, THEODORE F. W. SCHMIDT, residing at Anderson, in the county of Madison, in the State of Indiana, have invented a certain new and useful Improvement in Egg-Cases, of which the following is a description, reference being had to the accompanying drawings, forming part of this specification.

10 My invention has for its object the production of a simple, convenient, and efficient egg-case for retail trade, each case being preferably arranged to hold one dozen eggs. Its novelty will be hereinafter explained, and 15 particularly pointed out in the claims.

In the accompanying drawings, Figure 1 is a perspective view of the complete case, with the lid or cover in open position and with part of the front side or wall of the case 20 broken away to expose the parts within; Fig. 2, a middle longitudinal section, and Fig. 3 a cross-section.

The same letters of reference are used to indicate corresponding parts in all the views.

25 The complete case consists, essentially, of three parts—a suitable box or inclosing case, preferably formed of a single sheet of heavy paper or light strawboard, a strip of corrugated paper fitting in the bottom of said box 30 or case, either loosely or secured to said bottom, and a "filler" or set of partitions fitting within the box to divide its interior into separate cells for the reception of the eggs, the cross-pieces of such set of partitions or filler 35 projecting at their lower edges below the longitudinal strip of the partitions and fitting in the grooves of the corrugated paper, whereby they are held in proper position transversely of the case and displacement of them prevented.

In the accompanying drawings the box or casing inclosing the partitions is shown formed of a single sheet of paper, composed of a body portion A and a hinged top portion 45 or lid B, the latter being provided with a flap C, adapted to be tucked down within the front wall of the body of the box, between said wall and the front edges of the cross-partitions, to hold the lid closed. The inner thicknesses of the end walls of the box are also 50 shown provided with vertical extensions or

flaps D D, adapted to be bent inward and downward to horizontal position at the opposite ends of the box before the box is closed by its lid B in the manner described.

55

In the present instance the box is shown of suitable size and proportion to accommodate two longitudinal rows of six eggs each, and the filler consists of a middle longitudinal strip E and a series of cross-pieces F.

60

The method of securing the cross-pieces F to the longitudinal strip E will be apparent from Figs. 2 and 3, where it will be seen that the longitudinal strip E is provided with a series of notches G in its upper and lower edges, while each cross-piece F is provided with a middle vertical slot H, connected at its lower end with the lower edge of the cross-piece by a curved slit I, which arrangement permits the cross-piece to be readily slipped over and applied to the longitudinal strip E and held in the notches of the latter. This particular method of attaching the cross-pieces to the longitudinal strip is not essential, although believed to be novel; but it is 70 to be noted that each of the cross-pieces projects below the lower edge of the longitudinal strip, which feature is novel and is essential to their proper coöperation with the corrugated bottom of the box. This corrugated 80 bottom consists of a strip of corrugated paper J of approximately the size of the bottom of the box, with its corrugations running transversely thereof. It may be glued or otherwise permanently secured to the bottom of 85 the box; but I prefer to place it loosely in the box and to have its length slightly less than that of the bottom of the box to facilitate the fitting of the lower edges of the cross-pieces F into its corrugations. In assembling the 90 parts the corrugated bottom strip is placed in the bottom of the box and the filler or set of partitions placed upon it. By a very slight manipulation of the partitions the lower edge of each one of the cross-pieces F may be readily seated in one of the transverse grooves of the corrugated bottom, and when so seated the grooves will effectively hold the cross-pieces in proper position transversely of the box, so that the cells formed by the partitions 95 may be readily filled with eggs.

100

The body A of the box is formed slightly

flaring, so that a series of empty boxes with their lids open may be nested together and stored or shipped in compact form. The fillers or sets of partitions will likewise be flattened out to fit compactly together for storage or shipment with the boxes.

In the box shown in the drawings the upper forward corners of the cross-pieces F are rounded off to facilitate the insertion of the flap C of the lid between the front edges of the cross-pieces F and the front wall of the box.

I am aware that egg-cases intended for the same purpose as mine and composed of a box similar to mine and containing a filler composed of a middle longitudinal strip and a series of cross-pieces dividing the box into one dozen egg-cells have heretofore been used to a limited extent; but such boxes have not proved a success in the commercial handling of eggs, because they embodied no means for holding the cross-pieces of the filler in proper transverse position. In the absence of any such means such cross-pieces are readily displaced from proper position, and in ordinary rapid handling and assembling of the cases they will stand in various irregular positions, requiring them to be properly straightened as the case is filled with eggs.

In the commercial handling of eggs under the present general practice the cases are filled with eggs at the time the eggs are tested by "candling" them, and inasmuch as the eggs are handled with great rapidity in such operation it is necessary, unless the speed of the work is to be seriously interfered with, that the cells of the cases in which the tested eggs are to be placed shall be ready to receive them without the necessity for any adjustment of the partitions. My improved egg-case meets this requirement completely and overcomes the objections which have proved commercially fatal to the similar egg-cases not embodying my improvement.

Having thus fully described my invention, I claim—

1. The herein-described egg-case, consist-

ing of the long narrow box adapted to receive two longitudinal rows of eggs, the corrugated bottom in said box having its corrugations extending transversely thereof, and the filler or set of partitions fitting within the box and composed of a middle longitudinal strip and a series of cross-pieces attached to said strip and projecting below its lower edge and fitting the transverse grooves in the corrugated bottom, substantially as described.

2. The herein-described egg-case, composed of the box having its body A, lid B, and flap C formed of a single piece of paper, the corrugated bottom J in said box, and the set of partitions fitting in the box and composed of the middle longitudinal strip E and the cross-pieces F attached thereto and projecting below its edge and fitting in the transverse grooves in the corrugated bottom J, substantially as described.

3. The herein-described egg-case, composed of the box having its body A, hinged lid B, flap C, and end flaps D D formed of a single sheet of paper, the corrugated bottom J loosely fitting in said box and adjustable longitudinally thereof, and the set of partitions fitting in said box and composed of the middle longitudinal strip E and the cross-pieces F attached thereto and projecting below its lower edge and fitting in the transverse grooves of the corrugated bottom J, substantially as described.

4. The combination, with the box and its corrugated bottom, of the longitudinal strip E provided with the notches G in its upper and lower edges, and the cross-pieces F provided with the middle vertical slots H and curved slits I coöperating with the notches G in the strip E in the manner described, and projecting below the lower edge of the strip E and fitting in the transverse grooves of the corrugated bottom of the box.

THEODORE F. W. SCHMIDT.
